ICE BUCKET OR SIMILAR ARTICLE

Ralph R. Olswang, Scarsdale, N. Y.

Application June 23, 1955, Serial No. 36,653

Term of patent 3½ years

(Cl. D58—25)

The figure shows a perspective view of an ice bucket or similar article embodying my new design. The opposite side of the ice bucket is the same as the side shown.

I claim:

The ornamental design for an ice bucket or similar article, as shown and described.
